OIL ECONOMIZING SYSTEM FOR COMPRESSORS

Filed Nov. 3, 1941

FIG. 1.

UNITED STATES PATENT OFFICE

2,311,655

OIL ECONOMIZING SYSTEM FOR
COMPRESSORS

Walter R. Freeman, Clayton, and Cyril B. Fites,
St. Johns, Mo., assignors to Wagner Electric
Corporation, St. Louis, Mo., a corporation of
Delaware

Application November 3, 1941, Serial No. 417,602

6 Claims. (Cl. 230—30)

In a fluid compressing system, such as one for air, and comprising a compressor, a storage tank, unloading valve, and a lubricating system, a considerable amount of lubricant, such as oil, is wasted by becoming mixed with the compressed fluid and carried to the storage tank. This loss of oil not only necessitates careful checking to ascertain whether the supply is sufficient, but also causes trouble as a result of its mixture with water vapor to form a congealed mass which may easily prevent free flow of compressed air through the conduits.

One of the objects of our invention is to provide an improved oil economizing system for association with a compressor system which will extract the oil from the compressed air and return it to the oil reservoir prior to the entry of the compressed air into the storage tank.

A more specific object of our invention is to so associate an oil separating means with an air compressor system that the separated oil will be accumulated during the operation of the compressor and when the compressor is unloaded will be automatically caused to return to the oil reservoir through the same conduit which the compressed air passed to reach the separating means.

Other objects of our invention will become apparent from the following description taken in connection with the accompanying drawing in which Figure 1 is a view of a combined air compressor system and oil economizing system embodying our invention, parts being shown in section; Figure 2 is a sectional view of the principal oil separator; and Figure 3 is a sectional view of the combined unloading valve means and the oil dome venting valve means.

Referring to the drawing in detail, numeral 1 indicates the stator of a rotary compressor in which is reciprocably mounted a rotor 2 mounted on the shaft 3 driven by a pulley 4. The rotor is provided with a plurality of circumferentially spaced blades 5 (one only being partly shown in Figure 1). The shaft 3 of the stator is journaled in end plates 6 and 7, the end plate 6 being provided with the inlet passage 8 for the compressor. A casing 9 is secured to the end plate 7 to form an oil dome or oil reservoir 10 from which the compressor is lubricated. The oil in this dome is under pressure and thus oil will be forced under pressure into the compressor for lubricating purposes. The means employed to conduct oil from the oil dome to the compressor comprises a conduit 11 carried by the closure plate 7 opposite the end of the shaft 3 and extending down into the bottom of the reservoir. The conduit communi-

cates with a passage 12 in the rotor shaft, which passage communicates with a slot 13 in the rotor to permit fluid to be conveyed to the different parts of the compressor. The rotary compressor, 5 when in operation, will have chambers between the blades which are under sub-atmospheric pressure and this, in addition to the pressure on the oil in the oil dome, insures that there will be a sufficient flow of oil into the compressor for all required lubricating purposes.

The end plate 7 is provided with the discharge passage 14 for the compressor, which discharge passage communicates with a tube 15 extending upwardly to a point above the oil level in the oil dome. 15 On the end of this tube is mounted a preliminary oil separator 16 for removing the larger particles of oil from the compressed air, said particles being mixed with the air during the compressing operation. The large particles of oil are 20 separated from the compressed air as a result of the compressed air being forced outwardly through the passages 17 and against the inner wall 18 of the separator. By causing the oil laden air to impinge on the walls, the oil will be separated and collect on said walls from where it will 25 run back into the main body of oil in the oil dome.

Compressed fluid which has been discharged into the top of the oil dome after passing through the preliminary oil separator 16 is free to pass 30 out through the passage 19 associated with the top of the oil dome and to enter the conduit 20 leading to the main oil separator 21 which is so constructed as to remove substantially all of the remaining oil in the compressed air and particularly the mist and extreme small particles which 35 were not removed by the preliminary oil separator 16.

The main oil separator 21, which is shown in detail in Figure 2, comprises an upright cylindrical casing 22 provided with a bottom member 23 having a central bore 24 to which is connected the conduit 20 leading from the oil dome. The connection between the conduit 20 and the bore 24 comprises a fitting member 25 having a central passage 26 leading to the bore and radial passages 27 leading to an annular chamber 28 formed by a groove in the fitting and the wall of the bore. The inner end of the fitting through which the passage 26 extends has associated therewith a disc valve element 29 resting on the end of the fitting but free to be moved upwardly so that fluid can flow from the passage 26 to the bore by moving the disc upwardly and then passing around the disc through the slots 30 in the edge thereof. The upper end of the bore 24 communicates

with a tube 31 which extends upwardly through the cylindrical casing 21 to a point adjacent the top end wall thereof. Secured to the upper end of this tube is an inverted cup-shaped member 32 having its cylindrical wall 33 surrounding the tube in spaced relation. Passages 34 at the upper end of the tube 31 permit communication between the tube 31 and the top of the cup-shaped member. The outer wall of the tube 31 is provided with a plurality of baffles 35 and the wall 33 of the cup-shaped member is also provided with baffles 36. The baffles on the tube and member 32 are alternately arranged so that the fluid which is discharged in the top of the cup-shaped member must pass back and forth between the baffles to reach the bottom of the cup-shaped member. Thus, by means of these baffles, it is seen that the direction of flow of the compressed fluid is changed a number of times and said compressed fluid as it flows around the baffles is caused to impinge upon a plurality of surfaces. Oil will be collected on these surfaces and then run down into the bottom of the cylindrical casing 22 of the separator. During the passage of the compressed air around the baffles, some condensation of the oil in the air also takes place, thereby aiding in the removal of the oil.

The compressed air, after passing the baffles, will be free to pass out through the outlet passage 37 at the top of the separator from where it may enter the conduit 38 which leads to the storage tank (not shown). The outlet passage 37 has associated therewith a check valve 39 which is biased on its seat by a light spring 40. This check valve does not appreciably restrict flow of the compressed air from the separator to the tank but prevents any return flow.

The bottom 23 of the separator 21 is provided with a second bore 41 at one side of the bore 24. This bore 41 communicates with the bottom of the cylindrical casing by a passage 42 and also with the annular chamber 28 by a passage 43. Passage 42 has associated therewith a valve seat 44 and cooperating therewith is a check valve element 45 biased onto the seat by a light spring 46 interposed between the valve element and the plug 47 for closing the outer end of the bore 41.

The inlet passage 8 of the compressor has associated therewith a combined unloading valve and dome venting valve generally indicated by the reference numeral 48. These valves have a single casing 49 which is mounted on the end plate 6. Within the casing is an inlet passage 50 communicating with the angularly related passage 51 leading to the inlet passage 8 of the compressor. The inlet passage 50 has associated therewith an air cleaner 52 (Figure 1). At the juncture of the passages 50 and 51 is a valve seat 53 and cooperating therewith is a valve element 54 normally held off the valve seat by a spring 55. The valve element 54 has a piston portion 56 which extends into a chamber 57 where it can be acted upon by fluid pressure in said chamber. A conduit 58 places this chamber in constant communication with the conduit 38, previously referred to, leading to the storage tank from the main oil separator 21. Thus, the air pressure in the chamber 57 is always the same as that in the air tank. The piston head 56 of the valve is sealed by a diaphragm 59, the peripheral portion of which is held sealed by a spring 60.

The casing 49 of the combined unloading and venting valve mechanism is also provided with a stepped bore 61, the axis of which is at an acute angle to the axis of the passage 51 and communi-

cates with said passage by a passage 62. The shoulder 63 of the stepped bore has associated therewith a valve sealing ring 64 and cooperating with the ring is a piston 65 normally held off the sealing ring by a spring 66. The piston has an extension 67 provided with a conical end 68 forming a valve element for cooperation with a valve seat 69 formed on a closure plug 70 for the outer end of the stepped bore. This valve seat is associated with a passage 71 which communicates by a conduit 72 with passage 19 leading out of the top of the oil dome. The larger bore of the stepped bore is in constant communication with the passage 50 by way of a passage 73.

Between the passage 51 and the inlet passage 8 of the compressor there is provided a check valve 74 which prevents any air under pressure which might be developed by the compressor under certain conditions from being forced out through passage 51. The check valve element permits substantial free flow of air to the compressor.

Referring to the operation of the compressor, when the compressor is compressing air, the parts of the combined unloading and venting valve mechanism will be in the positions shown in Figure 3. The passage 71 will be closed and, therefore, the oil dome will be sealed. The valve element 54 will be maintained off its seat by the spring 55. Thus, air under atmospheric pressure may be drawn through the air cleaner, passage 50, and passage 41, from the inlet passage to the compressor where it will be compressed. During the compressing operation a certain amount of oil in the form of mist and small particles will be mixed with the air and be forced out with the compressed air through the discharge passage 14. This compressed air containing oil will pass through the conduit 15 and the preliminary oil separator which, as previously noted, will cause part of the oil and particularly the large particles to be removed from the compressed air. The compressed air in the oil dome will also act on the oil in the reservoir to force oil into the compressor in the manner already noted.

Compressed air, after entering the top portion of the oil dome, will pass through the outlet passage 19, the conduit 20 and into the main oil separator 21. From here it will be caused to pass back and forth over the baffles where substantially all of the remaining oil mixed with the compressed air will be removed and collect in the bottom of the cylindrical casing 22. The compressed air now free of oil will pass out through the check valve 39 and into the storage tank.

After the compressor has operated a sufficient time to bring the pressure in the storage tank up to a predetermined value, the unloading valve 54 will be closed against the bias of the spring 55 of predetermined strength. This closing is brought about by the air pressure in chamber 57 which is in constant communication with the storage tank through the conduit 58. When the valve element 54 is closed, air can no longer enter the compressor and, therefore, the compressor will cease its compressing operation and become unloaded. The continued rotation of the compressor rotor, however, will cause a sub-atmospheric pressure to develop in the inlet passage 8 and the passages 51 and 62. This will thus cause the piston 65 to be moved onto the sealing ring 64 due to the differential pressure acting on said piston. The movement of the piston will open the passage 71 and thereby place the dome in communication with the atmosphere by way of passage 73, pas-

sage 50, and the air cleaner. With air pressure relieved from the dome, no excess oil will be forced into the compressor during the unloaded period.

As long as there is air pressure in the dome, the valve element 45 at the bottom of the main oil separator 21 remains closed since the pressure on each side is equal and the spring 46 acts to hold the valve seated. When the dome becomes vented to atmosphere, the air pressure in passage 26, the annular chamber 28 and the bore 41 drops to atmospheric pressure. The air pressure in the main separator 21, however, does not drop to atmosphere due to the fact that the disc valve 29 is seated by gravity. The super-atmospheric pressure remaining in the main oil separator will thus act to open the check valve element 45 and permit the oil which has accumulated in the bottom of the oil separator to flow through passage 42, passage 43, annular chamber 28, passage 27, conduit 20, and passage 19 to the oil dome. When the oil is removed to the dome and the pressure in the separator is atmospheric, the valve element 44 becomes reseated. It is to be noted that the main oil separator should preferably be mounted above the top of the oil dome so that the oil will flow freely back into the oil dome when the valve element 44 is unseated. However, this is not always necessary since there will be a high pressure in the main oil separator which can force the oil back into the oil dome.

When the pressure in the tank drops sufficiently that the valve element 54 can be opened by spring 55, the compressor will again begin the compressing operation. When the suction is broken in passage 51, the valve element 67 will be seated, thereby closing the dome to atmosphere.

Our oil economizing system has been found to be very efficient in operation. Substantially all of the oil is removed from the compressor before it enters the storage tank. Because of this it is not necessary to constantly be watching the oil level in the oil dome. Also, there is little danger of the tubes becoming clogged by a mixture of oil and water. The arrangement is also such that the oil which collects in the main oil separator will not be returned to the oil dome until the compressor becomes unloaded and then it is caused to be forced back into the dome under pressure. Thus, the conduit 20 through which the oil is returned to the dome, will always be cleared of oil so that there will be none left therein that can be forced back into the main oil separator when the compressor again operates to compress air.

Being aware of the possibility of modifications in the particular structure herein described without departing from the fundamental principles of our invention, we do not intend that its scope be limited except as set forth by the appended claims.

Having fully described our invention, what we claim as new and desire to secure by Letters Patent of the United States is:

1. An oil separating system for association with a fluid compressor having an unloading valve and an oil reservoir associated therewith, said system comprising an oil separator having an oil accumulating chamber, conduit means for placing the separator in communication with the discharge outlet of the compressor to thereby convey the compressed fluid and oil carried therewith to the oil separator for separation of the oil thereby, a fluid pressure outlet from the separator, conduit means for conveying the separated oil from the accumulating chamber to the reservoir, a

5 valve associated with the last named conduit means for preventing oil from returning to the reservoir, and means for causing said valve to be opened automatically when the compressor is unloaded by operation of its unloading valve.

2. An oil separating system for association with a fluid compressor having an unloading valve and an oil reservoir associated therewith, said system comprising an oil separator having an oil accumulating chamber, conduit means for placing the separator in communication with the discharge outlet of the compressor to thereby convey the compressed fluid and oil carried therewith to the oil separator for separation of the oil thereby, a 10 check valve for preventing compressed fluid returning from the separator to the compressor, a fluid pressure outlet from the separator, a check valve for said outlet preventing return of compressed fluid, conduit means for conveying the separated oil from the accumulating chamber to the reservoir, a valve associated with the last named conduit means for preventing oil from returning to the reservoir, and means for causing said valve to be opened automatically when the 15 compressor is unloaded by operation of its unloading valve to thereby permit the fluid under pressure trapped in the separator to force the accumulated oil into the reservoir.

3. An oil separating system for association with a fluid compressor having an oil reservoir in which the oil therein is subject to the pressure of the compressed fluid discharged from the compressor and also having valve means for unloading the compressor and venting the reservoir to atmosphere, said system comprising an oil separator having an oil accumulating chamber, conduit means for connecting the separator to the reservoir above the oil therein to thereby convey the compressed fluid and oil carried therewith to the oil separator for separation of the oil thereby, and means for permitting the separated oil accumulated in the oil separator to flow back into the reservoir only when the compressor is unloaded and the reservoir vented to atmosphere.

4. An oil separating system for association with a fluid compressor having an oil reservoir in which the oil therein is subject to the pressure of the compressed fluid discharged from the compressor and also having valve means for unloading the compressor and substantially simultaneously venting the reservoir to atmosphere, said system comprising an oil separator having an oil accumulating chamber, conduit means for connecting the separator to the reservoir above the oil therein to thereby convey the compressed fluid and oil carried therewith to the oil separator for separation of the oil thereby, and means for causing the fluid under pressure in the separator to act on the separated oil accumulated in the oil separator and force it back into the oil reservoir when said compressor is unloaded and the reservoir is vented to atmosphere, said means comprising a valve opened by a differential pressure created by venting of the reservoir.

5. An oil separating system for association with a fluid compressor having an oil reservoir in which the oil therein is subject to the pressure of the compressed fluid discharged from the compressor and also having valve means for unloading the compressor and substantially simultaneously venting the reservoir to atmosphere, said system comprising an oil separator having an oil accumulating chamber, conduit means for placing the separator in communication with the discharge outlet of the compressor to thereby convey the compressed fluid and oil carried therewith to the oil separator for separation of the oil thereby, a fluid pressure outlet from the separator, conduit means for conveying the separated oil from the accumulating chamber to the reservoir, a

outlet of the compressor to thereby convey the compressed fluid and oil carried therewith to the oil separator for separation of the oil thereby, a check valve for preventing return flow of compressed fluid from the separator, a compressed fluid outlet for the separator, a check valve for preventing return of compressed fluid through the separator outlet, conduit means for conveying the separated oil from the accumulating chamber to the reservoir, a valve associated with the last named conduit means and movable off its seat in the direction of the flow of oil from the accumulating chamber to the reservoir, said valve being subject to fluid pressure in the reservoir biasing it closed and opened automatically by the fluid pressure trapped in said separator when the compressor is unloaded and the reservoir vented to atmosphere to thereby permit the accumulated oil in the separator to be forced back into the reservoir.

6. An oil separating system for association with a fluid compressor having an oil reservoir in which the oil therein is subject to the pressure of the compressed fluid discharged from the com-

pressor and also having valve means for unloading the compressor and substantially simultaneously venting the reservoir to atmosphere, said system comprising an oil separator having an oil accumulating chamber, conduit means for connecting the separator to the reservoir above the oil therein to thereby convey the compressed fluid and oil carried thereby, a check valve associated with the conduit means for preventing return flow of fluid therethrough, an outlet from the separator for the compressed fluid, a check valve for preventing return of compressed fluid through the outlet to the separator, means providing a conduit from the oil accumulating chamber of the separator to the first named conduit means at a point between the check valve therefor and the oil reservoir, and a valve associated with the last named conduit and opened by a differential pressure for permitting oil to flow therethrough from the separator back to the oil reservoir only when the compressor is unloaded and the reservoir is vented to atmosphere.
